UNITED STATES PATENT OFFICE

EDWARD GOWEN BUDD, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

METALLIC DOOR AND LOCK MECHANISM THEREFOR.

1,214,892.

Specification of Letters Patent.

Patented Feb. 6, 1917.

Application filed July 3, 1915. Serial No. 37,795.

To all whom it may concern:

Be it known that I, EDWARD G. BUDD, a citizen of the United States, residing at Philadelphia, in the county of Philadelphia, State of Pennsylvania, have made a certain new and useful Invention in Metallic Doors and Lock Mechanism Therefor, of which the following is a specification.

The object of the invention is to provide a metallic door and lock mechanism which is of simple construction, economical to manufacture and efficient in operation.

A further object of the invention is to provide a door and lock mechanism of the character referred to wherein provision is made for housing the lock mechanism within the door structure and which mechanism is composed of few parts, easily removable, which are assembled in such relation as to avoid wear and which may be readily and easily removed without requiring the use of tools for the purpose.

Other objects of the invention will appear more fully hereinafter.

The invention consists substantially in the construction, combination, location and relative arrangement of parts all as will more fully hereinafter appear, as shown in the accompanying drawings, and finally pointed out in the appended claims.

In the accompanying drawings:—

Figure 1 is a view in elevation of the inner face of a door constructed in accordance with the principles of my invention.

Fig. 2 is a view in transverse section on the line 2, 2, Fig. 1 looking in the direction of the arrows.

Fig. 3 is a broken detail view in transverse section on the line 3, 3, Fig. 4, looking in the direction of the arrows.

Fig. 4 is a fragmentary view in elevation showing the inside face of a portion of the door, parts in section on the line 4, 4, Fig. 5, showing the arrangement of the lock mechanism.

Fig. 5 is a view in section on the line 5, 5, Fig. 4, looking in the direction of the arrows.

Fig. 6 is a view similar to Fig. 4 showing a portion of the outer face of the inside panel of the door showing the lock mechanism.

Fig. 7 is a view in section on the line 7,

7, Fig. 6, looking in the direction of the arrows.

55

The same part is designated by the same reference numeral wherever it occurs throughout the several views.

In its essential features a metallic door embodying my invention consists of two sheet metal panels suitably pressed to the required shape and contour and secured together at their edges to constitute the door, the panels being separated from each other a distance to afford an interior chamber or recess.

The lock mechanism consists essentially of a locking bolt, an operating lever handle therefor, and a spring normally acting to maintain the bolt projected. These parts are readily separable with relation to each other and they are not connected through any screws or other attaching devices, and the locking bolt is carried in a housing which is arranged within the chamber between the door panels and suitably secured to the outer face of the inner door panel.

75

Referring particularly to the structure shown 6 designates the outer panel and 7 the inner panel of the door structure. Each of these panels is stamped out of sheet metal, the side and bottom edges of the inner panel being bent out of the plane of said panel as indicated at 8, 9, Figs. 2 and 3, and into suitable curved shape or form along the front edge of the door to receive and overlie the rubber or other bumper blocks and guiding lugs as indicated at 10. At its extreme edge bounding the vertical sides and lower edge of the door the flanged portions 8, 9, of the inner panel are formed into lips 11, over which are engaged bent flanges 12, at the bounding edges of the outer panel 6, as clearly shown in Figs. 2 and 3. Of course the inner and outer wall panels are formed into the desired shape and contour to follow the outlines of the vehicle or other structure to which the door is to be applied.

90

The inner panel 7 is pressed into shape to form a depression 13, centrally in the inner surface thereof, that is, the surface which is presented to the interior of the vehicle body. Across the lower portion of the open face of the depression or seat is secured a plate 35, thereby forming the pocket with which automobile doors are or-

95

100

105

dinary provided. If desired a strengthening bumper or filler plate 36 may be inserted between the outer surface of the wall of the depression and the inner surface of the outer door panel 6, as clearly shown in Figs. 1 and 2, although this is not essential. This structure of door and pocket is exceedingly simple, efficient, satisfactory and inexpensive to produce. The door hinge straps 14 through which the door is hinged to the adjacent post of the doorway are suitably secured into the door structure at the rear edge thereof. A simple and very satisfactory way of accomplishing this is shown wherein the ends 37 of the hinge straps extend through slots in the inner panel 7, into the space or chamber between the panels, and are welded or otherwise integrally connected to the inner surface of the flange 8 at the rear vertical edge of the door. This produces a strong durable structure which is economical to manufacture. Adjacent the front edge of the door structure the inner panel is provided in its inner surface with a depressed seat portion 15 stamped therein to receive and accommodate the handle 16 of the lock mechanism. The inner panel is slit at 17 to permit the lever 16 to extend through the slit and into the interior chamber 18, formed between the two panels 6, 7. The bolt 19 is housed within chamber 18, and its outer end projects through an opening formed in the flange 9 at the front edge of the inner panel, said bolt being retained in place by a housing or strap 20, in the form of a metal channel 20, having edge flanges which are applied and secured to the inner surface of the panel 7, or to a plate 38 which is applied to the inner surface of said panel. This plate has a looped end 39 which carries a stud 21 which is straddled by a fork formed at the inner end of lever 16, when said lever is in working position, thereby forming a fulcrum about which said lever rocks in operating the bolt. The bolt is engaged in any suitable manner by the lever 16. A simple arrangement is shown wherein the bolt on its inner face or surface is recessed as indicated at 22, and in assembling the bolt and its operating lever 16, the latter passes transversely through said depression. On its rear edge the lever 16 is formed with a rounded projection 23 which works against the inclined wall or surface 24 which forms a rear boundary of the depressed seat 22 in the bolt. This materially reduces friction and secures an easy operation of the bolt. Adjacent the extremity of the rounded projection 23 of the lever said lever is provided with a shoulder 25, see Fig. 4, into which extends the extreme outer corner 26 of the adjacent wall of the recess 22, thus forming a stop to normally retain the lever in its assembled relation with respect to the bolt. A coil

spring 27 is inserted within the housing 20 and normally exerts its tension against the inner end of the bolt in a direction tending to project the bolt outwardly. The engagement of the lever 16 in the depression 22 of the bolt, of course prevents the bolt from being withdrawn endwise from its housing. The depressed portion 15 in the inner panel not only accommodates the lever 16 in its rocking movement but it enables said lever to be brought into proper alignment with the seat or depression 22 in the bolt to enable the lever to be inserted through said depression 22 or to be withdrawn therefrom. In the particular form shown the depression 22 in the bolt is formed diagonally across the bolt. While this is a simple arrangement my invention is not to be limited or restricted in this respect.

In order to assemble the parts of the lock the spring 27 is inserted into the housing 20 and then the bolt is inserted so as to bear against the spring and is pressed inwardly as far as possible. This will bring the seat 22 in the bolt in line with the slit or opening 17 in the inner panel and into position for the lever 16 to be inserted through said slit 17 and through the housing 20 and through the seat or depression 22, and into position for the forked end thereof to engage the stud 21, the corner 26, when the bolt is released after inserting the lever, snapping against the shoulder 25 and the rounded surface or projection 23 bearing against the wall 24 of the recess 22. The parts are now in position assembled for operation. In order to remove the lock mechanism the reverse of the above operation takes place; that is to say, the bolt is pressed inwardly as far as it will go, this action releasing the projection 26 from shoulder 25, and then the lever 16 may be readily and easily withdrawn endwise through the seat 22. The bolt may then be pulled out and the spring removed from the housing. A lock mechanism such as has been described is exceedingly simple and economical to manufacture, is rugged and capable of withstanding rough usage without impairment. There are no wearing parts to get out of order and the parts may be detached, removed, and reassembled with ease and facility. No screws or similar securing devices for the parts of the lock are employed and which would be likely to work loose. Moreover, the door structure may be subjected to the usual enameling heat with the spring of the lock mechanism removed and consequently the danger of injuring the temper of the spring through the action of the enameling heat is avoided.

It will also be observed that no tool is required in order to effect the assembling or removal of the lock structure.

If desired, and in order to impose a desirable friction upon the bolt operating lever,

and to hold the same in the proper plane of operation a rib 28 may be stamped in the depressed portion 15 of the inner panel and arranged to extend transversely of the lever 16 5 and against which the lever operates.

Interposed between the upper edges of the inner and outer panels 6, 7, I prefer to insert suitable means for attaching a finishing material or strip for the door. A simple arrangement is shown wherein a box shaped stamping 29 is inserted between the upper edges of the stampings 6, 7, said stampings at their upper edges being suitably bent outwardly or away from each other to form a suitable seat for the member 28 therebetween and the extreme edge of one of said panels, as for instance, the outer panel 6 is bent over the upper side or edge of the member 29. All of the parts constituting the door structure, and including the housing 20 may be integrally secured together or to their adjacent parts integrally in any suitable or convenient manner. For convenience of manufacture I prefer to spot weld the parts, thereby avoiding joints which are liable to crack, get loose or to give trouble.

It will be understood that many variations in the details would readily occur to persons skilled in the art and still fall within the spirit and scope of my invention. I do not desire, therefore, to be limited or restricted to the exact details shown and described. But having now set forth the objects and nature of my invention and a construction embodying the same, what I claim as new and useful and of my own invention, and desire to secure by Letters Patent, is,—

1. In a metallic door structure, an inner and an outer panel offset from each other, one of said panels having a portion terminating in a laterally extending lip at its bounding edges, said flange portion being curved to receive and overlie the bumper blocks carried thereby, the other of said panels having its edges bent or turned over said lip and integrally secured thereto.

2. In a metallic door structure, an inner and an outer sheet metal panel, one of said panels having a flange portion along its side and bottom edges, said flange portion bent out of the plane of the body of said panel and terminating in a laterally extending lip, the adjacent edge of the other panel being bent inwardly over said lip, and a channel shaped stamping interposed between said panels along the upper edges thereof, the upper edge of one of said panels having a lip turned inwardly over the adjacent edge of said stamping.

3. In a metallic door structure, metal panels offset from each other and secured together at their edges to form an interior chamber between them, a bolt housing positioned within said chamber, a bolt loosely fitting said housing, a spring seated in the

housing and against which the bolt bears, one of said panels having an opening therethrough, an operating lever extending through said opening into said chamber and through said housing, and having engagement with said bolt, and means detachably engaged by said lever to form a fulcrum therefor whereby said lever may be readily detached and removed to permit the removal of the bolt.

4. In a door structure, panels having their body portions offset from each other and secured together at their edges to form an interior chamber, a housing extending into said chamber, a spring and bolt removably arranged within said housing, said bolt having a recess in one face thereof and an operating lever arranged to be removably inserted into said chamber and transversely through said housing and through said recess to operate said bolt.

5. In a door structure, panels offset from each other and having edge flanges secured together to form an interior chamber, a housing extending into said chamber, a spring and bolt removably arranged within said housing, said bolt extending through the edge of one of said panels and having a recess in one face thereof and an operating lever arranged to be removably inserted into said chamber and transversely through said housing and said recess, said lever having a rounded projection to work against the inner wall of said recess.

6. In a door structure, panels offset from each other and secured together at their edges to form an interior chamber, a housing arranged within said chamber, a spring and bolt removably arranged within said housing, said bolt having a recess in one face thereof and an operating lever arranged to be removably inserted into said chamber and housing and through said recess, said lever having a shoulder arranged to be engaged by a wall of said recess to retain said lever in place.

7. In a door structure, panels offset from each other and secured together at their edges to form an interior chamber, a housing extending into said chamber, a spring and bolt removably arranged within said housing, said bolt having a recess in one face thereof and an operating lever arranged to be removably inserted through one of said panels into said chamber and housing and through said recess, said panel having a depressed portion to accommodate the exteriorly extending portion of said lever.

8. In a door structure, panels offset from each other and secured together at their edges to form an interior chamber, a housing arranged within said chamber, a spring and bolt removably arranged within said housing, said bolt having a recess in one face thereof and an operating lever arranged to

be removably inserted through one of said panels into said chamber and housing and through said recess, said panel having a depressed portion to accommodate the ext-
6 eriorly extending portion of said lever and a rib or projection formed in said depressed portion in a direction transverse to said lever.

9. In a door structure, panels offset from each other and secured together at their edges to form an interior chamber, a housing arranged within said chamber and between said panels, a spring and bolt removably arranged within said housing, said bolt having a recess in one face thereof and an operating lever arranged to be removably inserted through one of said panels into said chamber and housing and through said recess, a pin or stud arranged within said 15 chamber, the inner end of said lever being forked to engage said pin or stud to fulcrum thereabout.

10. In a door structure, panels offset from each other and secured together at their edges to form an interior chamber, a housing arranged within said chamber and between said panels, a spring pressed bolt removably arranged within said housing, said bolt having a diagonally extending recess in 20 one face thereof, and an operating lever arranged to be removably inserted through one of said panels and into said chamber and housing and through said recess to operate said bolt.

35. 11. In a door structure, an inner and an outer sheet metal panel secured together at their edges in offset relation to each other to form a chamber therebetween, a housing arranged within said chamber and between 40 said panels and secured to the outer face of the inner panel, a bolt removably mounted in said housing and having its end projected through said panel at its edge, said panel having an opening, and a detachable bolt 45 operating lever extending through said opening and into said chamber and transversely through said housing, and removably engaging said bolt.

12. In a door structure, an inner and an outer sheet metal panel secured together at their edges in offset relation to each other to form a chamber therebetween, a channel shaped housing arranged between said panels and within the chamber and secured 55 therein, a bolt removably received in said housing, one of said panels being slotted adjacent said housing, and a bolt operating lever removably inserted through the slit in said panel and transversely through said 60 housing and detachably engaging the bolt to operate the same.

13. In a door structure, an inner and an outer sheet metal panel secured together at their edges in offset relation to each other to 65 form a chamber therebetween, a channel

shaped housing arranged between said panels and within the chamber and secured therein, a bolt removably received in said housing, one of said panels being slotted adjacent said housing, and a bolt operating 70 lever removably inserted through the slit in said panel and transversely through said housing and detachably engaging the bolt to operate the same, said panel having a depressed portion adjacent the slit therein to 75 accommodate the exterior portion of said lever.

14. In a metallic door structure, an inner and an outer sheet metal panel, having engaging edge portions, and off-set from each other intermediate their edges to form a 80 chamber, the inner panel having a pocket pan portion pressed therein at its center, said pan portion extending into said chamber, 85

90. 15. In a metallic door structure, an inner and an outer sheet metal panel, having engaging edge portions, and off-set from each other intermediate their edges to form a chamber, the inner panel having a pocket pan portion pressed therein at its center, said pan portion extending into said chamber, and a plate applied to the inner surface of the inner panel and across the lower portion 95 of said pocket pan.

16. In a metallic door structure, an inner and an outer sheet metal panel, having engaging edge portions, and off-set from each other intermediate their edges to form a chamber, the inner panel having a pocket 100 pan portion pressed therein at its center, said pan portion extending into said chamber, and a strengthening or filler plate inserted between the base of said pan portion and the opposed surface of the other panel. 105

17. In a metallic door structure, an inner and an outer panel, the edge of the inner panel being bent laterally from the plane of the body part of said panel and terminating in a bent lip, the corresponding edge of the outer panel having a flange bent over said lip and secured thereto, and a hinge strap having one end extending through the inner panel and secured to the laterally bent edge portion thereof. 110

18. In a door structure, panels secured together at their edges and off-set from each other intermediate their edges to form an interior chamber, one of said panels having a slot therethrough, a locking bolt extending 120 into said chamber adjacent said slot, and an operating lever for said bolt, said lever having one end extending through said slot and detachably engaging said bolt.

19. In a door structure, panels secured together at their edges and off-set from each other intermediate their edges to form an interior chamber, one of said panels having a slot therethrough, a locking bolt extending 125 into said chamber adjacent said slot, an op- 130

erating lever having one end extending through said slot, a fulcrum pin carried by said panel with which said lever end detachably engages, said lever arranged to engage 5 said bolt, and a spring operating to normally project said bolt.

20. In a door structure, panels secured together at their edges, a bolt housing disposed between said panels, a bolt loosely inserted in said housing and extending beyond the end of the housing, a spring loosely inserted in the housing and normally operating to project the bolt, and a removable 10

lever extending through out of said panels and transversely through said housing, and 15 detachably engaging said bolt.

In testimony whereof I have hereunto set my hand in the presence of the subscribing witnesses, on this 29th day of June A. D., 1915.

EDWARD GOWEN BUDD.
